(57) **CLAIM**

The ornamental design for a rod type water spray toy, as shown and described.

DESCRIPTION

FIG. 1 is a perspective view of a rod type water spray toy showing my new design;

FIG. 2 is front elevational view thereof;

FIG. 3 is rear elevational view thereof;

FIG. 4 is a top plan view thereof; and

FIG. 5 is a bottom plan view thereof.

FIG. 6 is a left side view thereof;

FIG. 7 is a right side view thereof;

FIG. 8 shows one application of the present invention, dashed lines are not claimed herein; and,

FIG. 9 is a perspective view showing an application of the present invention, where a neck portion of the water supply toy has been compressed.

Portions of the claimed design are shown separated and bound by a bracket to indicate indeterminate length.
